UNITED STATES PATENT OFFICE.

HENRY LUTZ, OF DENVER, COLORADO.

TOBACCO-PIPE.

No. 928,674.

Specification of Letters Patent.

Patented June 1, 1909.

Application filed May 15, 1908. Serial No. 432,966.

To all whom it may concern:

Be it known that I, HENRY LUTZ, a citizen of the United States, residing in the city and county of Denver and State of Colorado, 5 have invented certain new and useful Improvements in Tobacco-Pipes; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

15 My invention relates generally to improvements in tobacco pipes, but more specifically to means for cleaning the pipe, whereby the stem and smoke passage communicating therewith, may be quickly and easily 20 cleaned.

My improved cleaning device consists of a stem or spine, adapted to enter a passage formed in the bottom of the pipe bowl, and also the opening in the stem of the pipe. 25 The opening in the bowl and the portion of the stem directly connected therewith, is preferably of considerable size, or larger than the passage in the mouth piece. Hence, the cleaner is made wider where it enters 30 the larger opening, the part which enters the mouth piece being relatively small. In order to facilitate the pipe-cleaning operation, the passage formed in the bowl of the pipe is open at the rear side of the bowl, and the cleaner 35 is provided with a knob or head exposed at the outer extremity of the said opening, to permit the turning of the spine or cleaning stem for cleaning purposes. This spine is also provided with what I term a stripper, 40 consisting of a button or disk having an opening which closely fits the larger portion of the spine, so that when the spine or cleaner is drawn through the stripper, the latter will remove the impurities or material 45 which has been taken out of the pipe by the turning of the spine. This stripper also protrudes rearwardly from the pipe bowl, and increases the size of the head of the spine.

Having briefly outlined my improved construction, I will proceed to describe the same 50 in detail, reference being made to the accompanying drawing, in which is illustrated an embodiment thereof.

In this drawing, Figure 1 is a side elevation of a pipe equipped with my improvements. Fig. 2 is a longitudinal section

taken through the same, the cleaning spine being shown in elevation, and the stripper in section. Fig. 3 is a view similar to Fig. 2, with the cleaning device removed. Fig. 4 is 60 a detail view of the spine. Fig. 5 is a view of the same, looking in the direction of arrow 5, Fig. 4. Fig. 6 is an end view looking in the direction of arrow 6, Fig. 5. Fig. 7 is an end view in detail of the stripper. Fig. 8 is a section taken on the line 8—8, Fig. 7.

The same reference characters indicate the same parts in all the views.

Let the numeral 5 designate the bowl of the pipe, whose stem portion 6, formed integral with the bowl, is provided with a passage 7, which intersects the bottom of the chamber 8 of the bowl and is open in the rear, as shown at 9. The forward extremity of the passage 7, communicates with a passage 10, 75 formed in the mouthpiece 12. This mouthpiece is fitted into the forward extremity of the stem, but may be readily removed, if desired.

The cleaning device comprises a spine or 80 stem 13, and a stripper 14. This spine, as shown in the drawing, consists of a flat piece of material, which may be composed of wood, or any other material, sufficiently hard and durable for the purpose. The rear portion 85 15 of the spine, or that engaging the passage 7, is wider than the forward portion 16, which enters the passage 10, of the mouthpiece 12. The spine 13 is provided with notches, or recesses 17, through which the 90 moisture that may accumulate on top of the spine may drop through and occupy the portion of the passage underneath.

The rear extremity of the spine is provided with a button or milled head 18, which 95 is secured to the spine in any suitable manner, as by a fastening device 19. This button may also be formed integral with the spine, if desired. The stripper 14, is provided with a narrow opening 20, of sufficient 100 size to receive the part 15 of the spine. This stripper normally occupies a position on the spine in contact with the head or button 18. The button and cleaner both protrude through the opening 9 at the rear side of the 105 pipe bowl, whereby both are accessible to the user of the pipe.

When it is desired to clean the pipe, the spine is turned therein. The passage is of sufficient diameter to permit the turning of 110 the flat portion 15 of the spine, while the passage 10 of the stem is large enough to

allow the spine part 16, to turn therein. As these flat parts 15 and 16, fit quite closely in their corresponding passages, it is evident that as the spine is turned, it will scrape out 5 the impurities in the passage which the spine engages. The spine is then withdrawn from the pipe, after which the user, while holding the stripper, draws the spine therethrough, thus scraping all of the impurities therefrom. 10 The spine is then placed back in the pipe and may be allowed to remain until the next cleaning operation becomes necessary.

It is evident that in smoking, the smoke will pass along over the top of the spine. 15 The spine, when in proper position, completely cuts off the forward portion of the space below from the smoke and suction, and makes it a receptacle for moisture.

Having thus described my invention, what 20 I claim is:

1. A tobacco pipe, having a longitudinal passage formed in the stem therein, and communicating with the receptacle in the bowl, one end of the said passage being open at the 25 rear of the bowl, a cleaning device located in the said passage and provided with a head or disk protruding from the rear side of the pipe bowl, the cleaner being formed flat and of a width equal, or approximately equal, to the 30 diameter of the passage in which it is located, whereby, as the spine is turned, the impurities of the passage will be scraped out, and a stripper plug having a narrow opening of uniform size, extending therethrough, and in 35 which the spine fits closely, substantially as described.

2. A tobacco pipe, whose stem is provided with a passage intersecting the bottom of the tobacco chamber in the bowl, one extremity 40 of the said passage being open at the rear side of the bowl, a cleaning device inserted in the said passage, and provided with a protruding head or button, and a stripper plug having a narrow opening of uniform size, extending 45 therethrough, and in which the spine fits closely, substantially as described.

3. A tobacco pipe comprising a bowl and a stem, the stem and bowl having a passage communicating with the chamber of the 50 bowl, the said passage being open at the rear side of the bowl, a stem or spine inserted in the said passage and protruding therefrom at the rear, and a stripper plug having a narrow opening of uniform size extending there- 55 through, and in which the spine fits closely, for the purpose set forth.

4. A tobacco pipe whose stem is provided with a longitudinally disposed passage communicating with a receptacle in the pipe bowl, the said passage being open at the rear 60 of the bowl, a stem or spine located in the said passage and provided with a protruding head, and a stripper plug having a narrow opening of uniform size extending there-

through, and in which the spine fits closely, 65 adjacent the head, for the purpose set forth.

5. A tobacco pipe composed of a head, stem and mouthpiece, the stem proper having a longitudinal passage intersecting the bottom of the bowl receptacle and being 70 open at the rear of the bowl, and a stem or spine entering the said passage and also the passage in the mouthpiece, the two passages being of different size, a stem or spine inserted in the said passages, the parts of the 75 spine entering the two passages being of different size, the extremity of the spine or stem protruding from the passage at the rear of the bowl, and a stripper plug having a narrow opening of uniform size extending therethrough, and in which the spine fits closely, 80 substantially as described.

6. A tobacco pipe whose stem is provided with a passage intersecting the bottom of the bowl receptacle, and a spine or cleaning stem 85 located in the said passage and provided with a stripper, for removing the impurities from the stem as the latter is drawn through the stripper, the latter consisting of a plug having a narrow opening of uniform size extending 90 therethrough, and in which the spine fits closely, substantially as described.

7. A tobacco pipe whose stem is provided with a passage intersecting the bottom of the bowl receptacle and having its rear extremity open, and a spine or stem having a flat portion entering the said passage, the latter being cylindrical, the width of the spine where it enters the said passage being of the same diameter, or approximately the same 100 diameter, as the passage, the rear extremity of the spine being provided with an exposed head to facilitate the operation of the spine, and a stripper plug having a narrow opening of uniform size extending therethrough, and in which the spine fits closely, for the purpose 105 set forth.

8. The combination with a tobacco pipe, of a spine which separates the smoke passage of the stem into upper and lower compartments, the upper space being in communication with the bowl and forming a passage for the smoke, while the lower space forms a separate receptacle for the moisture. 110

9. A tobacco pipe having its stem provided with a removable spine inserted in the smoke passage and forming a partition dividing the passage into upper and lower compartments, the spine being provided with openings to permit the moisture to pass from the upper to the lower compartment, substantially as described. 115

In testimony whereof I affix my signature in presence of two witnesses.

HENRY LUTZ.
